(57) CLAIM

The ornamental design for a cylindrical vacuum container, as shown and described.

DESCRIPTION

FIG. 1. is a first side elevational view of the cylindrical vacuum container showing my new design;

FIG. 2. is a second side elevational view thereof;

FIG. 3. is a third side elevational view thereof;

FIG. 4. is an exploded side elevational view thereof;

FIG. 5. is a top plan view thereof;

FIG. 6. is a top plan view thereof with the lid removed;

FIG. 7. is a bottom plan view thereof;

FIG. 8. is a perspective view of the base thereof; and,

FIG. 9 is a perspective view of the utensil thereof, shown separately for clarity of illustration.
